CLAIM

The ornamental design for a lite terminal, as shown and described.

DESCRIPTION

FIG. 1 is a front perspective view of a lite terminal showing our new design;

FIG. 2 is a front elevation view of the lite terminal shown in FIG. 1;

FIG. 3 is a rear elevation view of the lite terminal shown in FIG. 1;

FIG. 4 is a left side elevation view of the lite terminal shown in FIG. 1;

FIG. 5 is a right side elevation view of the lite terminal shown in FIG. 1;

FIG. 6 is a top plan view of the lite terminal shown in FIG. 1; and,

FIG. 7 is a bottom plan view of the lite terminal shown in FIG. 1.

(Continued)

The broken lines are included to show features that form no part of the claimed design.

1 Claim, 6 Drawing Sheets
